ENEA BOSSI, OF NEW YORK, N. Y., ASSIGNOR, BY MESNE ASSIGNMENTS, TO STEWART
WARNER SPEEDOMETER CORPORATION, A CORPORATION OF VIRGINIA.

VACUUM FEED SYSTEM.

Application filed November 23, 1920. Serial No. 425,950.

To all whom it may concern:

Be it known that I, ENEA BOSSI, a subject of the King of Italy, and a resident of New York, in the county of New York, State of New York, have invented new and useful Improvements in Vacuum Feed Systems, of which the following is a specification.

This invention relates broadly to feeds for hydrocarbon engines and more specially to a gasoline vacuum feed system.

The principal object of the present invention is to provide a vacuum feed system having balanced valve constructions in the vacuum line to permit efficient and accurate operation of the control valve.

Another object of the present invention is a vacuum feed device wherein a port area of the vacuum control valve is proportioned to the weight of the operating member therefor, to insure proper and correct operation of the valve.

A still further object of the present invention is a vacuum feed device comprising a pair of cylindrical containers with the axis of one container at substantially right angles to the axis of the other container.

Another object of the present invention is a vacuum feed device comprising an inner chamber and an outer chamber one of which is operatively connected with a suitable source of supply and the other of which is connected with a suitable gasoline engine and with open air vents provided in both of said chambers.

A still further object of the present invention is a vacuum feed system for hydrocarbon engines or the like wherein a plurality of control means are provided for the vacuum line and loosely connected freely movable float devices provided for operating said means.

A still further object of the present invention is a gasoline feed device comprising an inner cup-like chamber and an outer cylindrical chamber surrounding said inner chamber with a neck portion provided with a cylindrical space leading from the outer chamber and an air vent into said space and adjacent the upper end of both of said chambers.

Another object of the said invention is an air valve for a vacuum line constructed in such manner that a relatively light float member may be utilized to open the vacuum line when required.

A still further and important object of the present invention is a control valve for the vacuum line arranged adjacent an air cushion reservoir adapted to prevent undesirable movements of the valve due to surge-like impulses in the vacuum line produced by the action of the engine.

Another object of the present invention is a vacuum feed system, an outlet valve provided between the primary chamber with the axis of the valve conduit being substantially horizontal and with the valve seat being inclined to the axis in such manner that the opening of the valve tends to move the valve disk in an outward and upward direction.

Another important object of the present invention is a vacuum feed system comprising primary and secondary chambers with the secondary chamber surrounding the primary chamber and with a relief valve in the lower portion of the primary chamber located in such manner as to be normally immersed in fluid thereby reducing the hydrostatic or fluid head on the primary side of the valve disk and also acting as a damper to prevent chattering of the valve disk on its seat.

Another object of the present invention is a vacuum feed device wherein a relatively long primary chamber is surrounded by a secondary chamber in such manner that the gasoline in the secondary chamber may immerse a relatively large portion of the primary chamber and whereby the valves controlling the primary chamber are adapted to be operated by a relatively small variation in pressure.

Other and further objects of the present invention will be pointed out in the specification hereinafter following and will in part be obvious from the foregoing description of the device.

It is realized that the present invention may be embodied in constructions other than those specifically illustrated herewith, there-

fore, it is to be understood that the disclosure herewith is illustrative and not to be considered in the limiting sense.

In the accompanying drawings forming a part of this specification like characters are used to represent like parts throughout the several figures.

Figure 1 is a sectional view illustrating the arrangement of parts.

10 Figure 2 is an enlarged detail view taken on line 2—2 Figure 1.

Figure 3 is a sectional detail view taken on line 3—3 Figure 2.

15 Figure 4 is a view similar to Figure 3 showing the valve parts in a different position.

Figure 5 is a side view of the device.

Heretofore in a vacuum feed system it has been customary to provide a primary and a 20 secondary chamber, with these chambers located one above the other in such manner that the fluid in the secondary chamber did not tend to rise around the fluid in the primary chamber. In these types of constructions the valve leading from the primary chamber was subjected to fluid pressure of one side only. Thus having the effect of producing unbalanced conditions of the valve and the valve did not tend to seat easily under relatively low vacuum as was sometimes encountered in the primary chamber.

25 Furthermore in the vacuum systems heretofore known in the art it is customary to provide a control valve for the vacuum line which valve was adapted to be held closed by spring pressure controlled by a float in the primary chamber and the suction of the engine was also used in some constructions but the suction in most cases was slightly intermittent and there was a liability of the valve opening at undesired times. To overcome this difficulty it has been customary to provide springs and toggle constructions under control of float mechanism specified.

30 These toggle constructions add complications which render the device liable to disorganization and also adds to the cost of manufacture, assembly, and adjustment. It has likewise been customary in the art to use air valves for venting primary chamber and such valves were operated in such manner that when the vacuum line was open the air valve would be closed and vice versa. In

35 constructions of this character if the air valve failed to work the device did not operate satisfactorily and since the air valve was open and liable under road conditions to become clogged with dust it was not infrequent that the air valve failed to work on the road in the manner it operated in the laboratory.

40 The present invention overcomes the difficulties of the known art by providing an exceedingly simple construction in which a minimum number of working parts are

utilized in carrying out the desired result. Preferably two sets of valves are utilized, one being a float operated control valve for the vacuum line and the other being a fluid pressure operated valve for releasing the fluid from the primary chamber. Other valves may be utilized in the several lines as desired but such valves are not a part of the present invention. A further advantage over the known art is obtained by the present invention by the provision of interfitted primary and secondary chambers so constructed that the secondary chamber encloses the primary chamber. This economizes space and provides for immersing the outlet valve from the primary chamber in the liquid in the secondary chamber and thereby causes the head of the liquid in the secondary chamber to assist closing the valve when a vacuum is established within the primary chamber. Consequently the present device will operate properly under varying vacuum conditions since the limits of requirements of the device are small.

45 The primary control valve preferably is a balanced type of valve which is arranged adjacent a small expansion chamber that absorbs variations in vacuum impulses in the vacuum line and maintains substantially uniform pressure on both sides of the valve which are at right angles to the line of movement of the valve, since the valve is adapted to seat against one side of the valve wall instead of having the valve seat, the axis of which is parallel to the axis of movement of the valve. This permits the use of a large vacuum conduit and a relatively light float to open the valve.

50 Preferably the control valve is in the form of a double valve wherein the balanced valve specified is supplemented by a ball valve which is effective to prevent the balanced valve from dropping away from the valve seat when the vacuum is cut off from the primary chamber. The construction previously described insures of positive operation of the parts and especially adapts the device to be used on automobiles or the like having engines which run relatively free from vibration. At the same time the device is equally adaptable for use where great vibration is encountered. Both the primary and secondary chambers in the present invention are open to atmosphere through small valveless vents in such manner that the secondary chamber continually tends to drain to the carburetor and the primary chamber tends to drain immediately after the vacuum is cut off from the chamber. While the area of the suction port is sufficient to hold the ball valve seated when desired, this area of suction or vacuum port is so proportioned to the area of the inlet conduit port from the main gasoline tank that when a high vacuum occurs on the suction line (as

55 100 105 110 115 120 125 130

when the engine is idling) the tendency to quickly over-fill the primary chamber, and draw gasoline directly through the vacuum line before the control valve is seated by the 5 float, is obviated.

Referring now to the drawings and more specifically to Figure 1 the secondary casing which may comprise a sheet metal member 2 having a flange 4 and a neck portion 5. A 10 back plate 6 is adapted to extend over and rest upon the flange 4 with the edge of the back plate spun over the edge of the flange as at 7 and with suitable eyelets 8 comprising rivet members for sealing the flange and 15 the back plate and providing screw openings through which the device may be mounted as desired. The neck 5 is provided with a tubular casing 9 terminating in an annular bead 10. A primary chamber 11 may comprise a cup-like member having an annular flange 12 adapted to be seated on the bead 10 of the secondary casing. This primary chamber 11 is provided with an L-shaped conduit 14 which is held in position by a 20 threaded tubular stud 15 and the L-shaped conduit is provided on the outer end with a downwardly and outwardly inclined valve seat 16. A suitable spider 17 is mounted adjacent the valve seat and a valve disk 18 is 25 adapted to move back and forth between the spider and the valve seat to open and close the outlet of the conduit 14, as the device operates.

A cap member 19 is adapted to be held in 30 place over the flange 12 of the primary chamber 11 by means of machine screws 20 which pass through the flange of the cap member and press the gasket 21 tightly against the flange 12 thereby providing a 35 hermetic sealed joint. The cover member is arranged with a conduit 22 which is adapted to be connected to a gasoline tank or other suitable supply of liquid. This conduit 22 leads to a well 24 which is closed by a cap 40 held in position by a machine screw 26. The bottom of this well is covered by a screen 27 and is provided with a guide lip 28 which directs the flow of gasoline downwardly 45 along the said wall to the primary chamber 50 so that the gasoline does not strike the float with sufficient force to seriously counteract the buoyancy thereof. The cap member 19 carries a control valve casing, the body 29 of which is provided with a conduit 30 adapted to be connected with the intake side, such as a manifold, of a gasoline engine, in order that the vacuum may be established in the conduit 30 when the engine is running. This body member 29 is clamped in position 60 on the cap 19 by means of a nut 31, so that the body member 29 may be rotated to a desired position and then clamped to the cap 19 to facilitate making connections with the conduits on different mountings. A cylindrical valve seat 32 is provided in the body 65 portion 19 and a cylindrical valve 34 is adapted to cooperate with said seat. This valve is mounted for radial longitudinal and rotative movement on the valve stem 35 which passes through the opening 36 which is considerably larger than the valve stem and the valve is retained in position on the valve stem by means of disk-like retaining members 37 which are spaced apart a distance greater than the length of the valve 70 member.

Preferably this valve member is also provided with openings 38 which permit equalization of the fluid pressure on both sides of said valve member thereby providing a balanced valve. A guide cup 39 may be provided adjacent the upper end of the valve stem and where desired a stub 40 may be formed on the end of the stem. A cap 41 is seated over the guide stem and provides a small reservoir into which gas pressure may surge that would otherwise be effective upon the valve 34. This reservoir therefore has a stabilizing action on the operation of the device. A conduit 42 leads from beneath the valve 34 into the primary chamber and the lower end of this conduit preferably is formed into a conical valve seat as at 43 and is adapted to receive a ball valve 44 which may be used as a secondary valve to supplement the primary balanced valve 34. The valve stem 35 extends downwardly through a relatively large opening 45 in a float bracket 46 which is secured to the float 47. The valve stem carries on its lower end a head 48 which is adapted to engage with the float bracket 46 and permits the weight of the float 47 to open the valve against the vacuum pressure effective upon the main control valve. The primary reservoir 11 is provided with a small vent 49 which is at all times maintained open to atmosphere. This vent is proportioned in area to the vacuum conduit 42 in such manner that under normal conditions sufficient vacuum is maintained in the primary chamber to elevate the liquid or gasoline as is desired even though the vent 40 is fully open at all times. The secondary chamber 11 is also provided with a vent 50 which is likewise open to atmosphere at all times. This vent 50 is located in the tubular member 9 and leads to the annular space 51 formed between the member 9 and the side wall of the primary casing 11.

From the foregoing description it will appear that when the vacuum is established in the conduits 30 and 42, air will be exhausted from the primary reservoir, consequently air pressure will raise the gasoline or other liquid through conduit 22 and tend to fill the primary reservoir 11. The weight of the control valve and valve stem is sufficient to retain the vacuum conduit open consequently as the gasoline or other liquid fills the pri-

mary reservoir the float 47 rises until the float bracket 46 engages the ball valve 44 and lifts the control valve. As this valve is lifted the main balance valve 34 gradually closes the conduit 30 until only a very slight opening is left. At this time the ball valve engages the conical valve seat and the vacuum is sufficient to maintain the ball valve seated and the primary balance valve 19 is likewise moved to just close the vacuum line. There is a slight residual vacuum in the chamber formed by the cap 41 and this is sufficient to hold the valves closed against gravity since the weight of the valve parts is so proportioned as to insure this action. When this occurs atmospheric pressure entering through the vent 49 causes the liquid pressure in the primary chamber to be sufficient to unseat the valve disk 18 and permit the liquid of the primary chamber to enter into the secondary chamber which continues until the float 47 descends sufficiently so that the bracket 46 encounters the head 48 on the valve stem 35. At which time the ball valve 44 is unseated and the weight of the balance valve member and the ball valve member causes the control valve to open under force of gravity. The liquid in the secondary chamber is at all times under atmospheric pressure and may be drained by gravity to the carburetor or other device. During normal operations of the device the liquid in the secondary reservoir rises to a considerable height around the primary reservoir so that the valve disk 18 is normally immersed and consequently when the vacuum line is closed the hydrostatic height of the liquid in the secondary chamber is substantially equalized. The liquid head in the secondary chamber, as soon as the pressure is withdrawn from the surface of the liquid in the primary chamber, causes the disk valve 18 to close. The arrangement of the chambers in this compact relation facilitates the operation of the device and causes conditions in the secondary chamber to control to a certain extent the operation of the float in the primary chamber. This causes efficiency of the working parts and facilitates the operation of the device. In fact the whole of the factors such as port areas, weight of parts and effective pressures, as above explained are so counter-balanced and inter-related that all work in harmony.

In order that there may be no mistake concerning the application of the present invention as a gasoline feed for hydrocarbon engines, attention is directed to Figure 5 wherein a side view of the device is disclosed and diagrammatic connections are illustrated between the device and the main gasoline tank A and the gasoline engine C. The main tank A should be vented to atmos-

phere in order to permit the gasoline in the tank to be easily withdrawn without increasing the external pressure on the tank. The conduit 30 of the device is connected by a suitable conduit to the manifold B of the gasoline engine C, and the secondary casing 2 is connected by a suitable conduit with the carburetor D.

While a balanced and ball valve arrangement is illustrated as controlling the suction line, it is to be understood that the primary purpose of the secondary valve is to comprise a means whereby the suction may be regulated or reduced so that only a light weight is required to withdraw the ball valve, or an equivalent type of primary valve from its seat. When the ball valve is withdrawn a sufficient distance from the seat, the valve stem operates to withdraw the slide valve. This then establishes a full vacuum through the conduit 42. However, the ball or primary valve is a sufficient distance below the seat so that the strong suction does not tend to draw the ball valve back against the seat. By means of this double control of the vacuum line it will be seen that a more positive operation of the device is accomplished in that the float is proportioned to open the valve under an effective pressure which is much less than the actual pressure developed by the suction because the valve 32 being a slide valve is not directly affected in its operation by the direct action of the suction, whereas the primary valve 44 is affected in that the pressure established by the vacuum is directed at right angles to the seat on which the primary valve rests. While specific constructions have been illustrated it is to be understood that any means accomplishing this end is within the scope of the present invention.

Having thus described my invention, what I claim is:

1. In a vacuum feed device the combination of a primary reservoir, a vacuum line, a control valve in the upper portion of said primary reservoir and adapted to control the vacuum line, said control valve comprising a plurality of valve members effective to be simultaneously operative upon said vacuum line.

2. In a vacuum feed device the combination of a primary reservoir, a vacuum line, a control valve in the upper portion of said primary reservoir and adapted to control the vacuum line, said control valve comprising a cylindrical valve and a ball valve both effective to be simultaneously operative upon said vacuum line.

3. In a vacuum feed device the combination of a primary reservoir, a vacuum line, a control valve in the upper portion of said primary reservoir and adapted to control the vacuum line, said control valve comprising a plurality of valve members effective

to be simultaneously operative upon said vacuum line and a float adapted to seat one of said valve members.

4. In a vacuum feed device the combination of a primary reservoir, a vacuum line, a control valve in the upper portion of said primary reservoir and adapted to control the vacuum line, said control valve comprising a cylindrical valve and a ball valve both effective to be simultaneously operative upon said vacuum line and a float adapted to seat one of said valve members and the effective area of said last mentioned valve members being sufficient to cause said valve to be held seated by suction.

5. A vacuum feed device comprising a reservoir, a conduit leading into said reservoir and being adapted to be connected with a supply of gasoline or the like, a second conduit also leading to said reservoir and being adapted to be connected with means for producing suction, a control valve comprising a balanced valve and a ball valve both adapted to control the effect of said suction upon said reservoir, and means within said reservoir and rendered operative by the height of the fluid therein to operate said control valve.

6. A vacuum feed device comprising a reservoir, a conduit leading into said reservoir and being adapted to be connected with a supply of gasoline or the like, a second conduit also leading to said reservoir and being adapted to be connected with means for producing suction, said reservoir being vented to atmosphere at all times, a control valve comprising a balanced valve and a ball valve both adapted to control the effect of said suction upon said reservoir, and a float within said reservoir operative by the height of the fluid therein, and a loose connection between the float and the control valve to operate said control valve.

7. A vacuum feed device comprising a primary reservoir, a secondary reservoir, said secondary reservoir, a conduit leading from said primary reservoir to said secondary reservoir, a valve apparatus to close said conduit, both of said reservoirs being provided with openings to atmosphere, a conduit leading to said primary reservoir and being adapted to be connected with a suction apparatus, a valve stem, a valve on said stem for controlling said vacuum conduit and mounted for radial movement on said valve stem, and float operative means for operating said valve.

8. A vacuum feed device comprising a primary reservoir, a secondary reservoir, said secondary reservoir surrounding and enclosing said primary reservoir, a conduit leading from said primary reservoir to said secondary reservoir, a valve apparatus to close said conduit, both of said

reservoirs being provided with openings to atmosphere, a conduit leading to said primary reservoir and being adapted to be connected with a suction apparatus, a valve for controlling said vacuum conduit and float operative means for operating said valve, said valve comprising a cylinder with a valve seat on the side wall thereof and with an opening extending through the cylinder from end to end.

9. A vacuum feed device comprising a primary reservoir, a secondary reservoir, said secondary reservoir surrounding and enclosing said primary reservoir, a conduit leading from said primary reservoir to said secondary reservoir, a disk valve to close said conduit, the axis of the valve seat being inclined to the horizontal, both of said reservoirs being provided with openings to atmosphere, a conduit leading to said primary reservoir and being adapted to be connected with a suction apparatus, a valve stem, a balanced slide on said stem for controlling said vacuum conduit and mounted for radial movement on said valve stem, said valve comprising a cylinder with a valve seat on the said wall thereof and with an opening extending through the cylinder from end to end, and float operative means for operating said valve.

10. A casing for a vacuum feed device comprising a cylindrical body portion having a flange on one edge thereof, a back plate secured to said body portion adjacent said flange, and a cylindrical neck extending from said body portion, the axis of the cylindrical neck being at substantially right angles to the axis of the cylindrical body portion.

11. A casing for a vacuum feed device comprising a cylindrical body portion having a flange on one edge thereof, a back plate secured to said body portion adjacent said flange, the edge of the back plate being spun over the edge of said flange, eyelet members extending through said back plate and said flange, and a cylindrical neck extending from said body portion.

12. A vacuum feed system comprising a chamber adapted to receive liquid, a conduit connected to said chamber and leading to a suitable supply of liquid, a second conduit adapted to be connected with means for producing a suction, and a plurality of valve members simultaneously operative for controlling said suction.

13. In a vacuum feed system or the like, a vacuum conduit, an intermittently operated control valve adapted to be retained in closed relation by differential pressure established by suction and means for controlling the suction in such manner as to maintain a lesser degree of suction in the conduit adjacent said valve when the valve

is seated and to permit full suction to be effected in said conduit when the valve is open.

14. In a vacuum feed system or the like, a vacuum conduit, a reservoir, an intermittently operated control valve adapted to be retained in closed relation by differential pressures established by suction means for controlling the suction in the conduit leading to the control valve in such manner as to maintain a lesser degree of suction in the conduit adjacent said valve when the valve is seated and to permit full suction to be effected in said conduit when the valve is open, and a float in said reservoir to operate said means.

15. In a vacuum system or the like, a suitable reservoir, a vacuum conduit connected to said reservoir, a valve operative in said vacuum conduit in such manner that differential pressures established by the vacuum in said conduit are adapted to retain said valve seated to close the conduit, and means for reducing the effective vacuum on said valve when said valve is seated.

16. In a vacuum system or the like, a suitable reservoir, a vacuum conduit connected to said reservoir, a valve operative in said vacuum conduit in such manner that differential pressures established by the vacuum in said conduit are adapted to retain said valve seated to close the conduit, means for reducing the effective vacuum on said valve when said valve is seated, and float means to seat and unseat said valve.

17. In a vacuum feed system or the like, a reservoir, a vacuum conduit leading to said reservoir, a valve adapted to close said conduit and with the valve arranged to be held seated by differential pressure established by the suction through said conduit, a chamber adjacent said valve and communicating with said conduit, and means adapted to cut off the suction from said chamber when said valve is closed.

18. In a vacuum feed system or the like, a reservoir, a vacuum conduit leading to said reservoir, a valve adapted to close said conduit and with the valve arranged to be held

seated by differential pressures established by the suction through said conduit, a chamber adjacent said valve and communicating with said conduit, and means adapted to cut off the suction from said chamber when said valve is closed and to retain the suction cut off until after said valve is opened.

19. In vacuum feed system or the like, a reservoir, a vacuum conduit leading to said reservoir, a valve adapted to close said conduit and with the valve arranged to be held seated by differential pressures established by the suction through said conduit, and means adapted to reduce the effect of the suction upon said valve when said valve is closed.

20. In a vacuum feed system or the like, a reservoir, a vacuum conduit leading to said reservoir, a valve adapted to close said conduit and with the valve arranged to be held seated by differential pressures established by the suction through said conduit, a chamber adjacent said valve and communicating with said conduit, and means adapted to reduce the suction from said chamber when said valve is closed and to retain the suction reduced until after said valve is opened.

21. In a vacuum feed system or the like, a reservoir, a vacuum conduit leading to said reservoir, a valve for closing said vacuum conduit with reference to said reservoir, a chamber adjacent said valve and connected to said vacuum conduit and to the conduit leading to the seat for said valve, and means for reducing the effect of the vacuum produced in said conduit when said valve is closed.

22. In a vacuum feed system or the like, a reservoir, a vacuum feed conduit operatively connected with said reservoir, a valve in the end of said conduit within the reservoir, and adapted to be held seated by a vacuum, means to reduce the vacuum effective on said valve when said valve is closed, and devices to open said valve and operate said means and being adapted to open said valve before operating said means to increase the effect of the vacuum.

ENEA BOSSI.
